RETARDED ELECTRIC INTERRUPTER
AND SWITCH

Aldo Giordani and Aronne Giordani, Padua, Italy

Application February 21, 1935, Serial No. 7,591
In Italy February 27, 1934

2 Claims. (Cl. 200—35)

This invention relates to retarded electric interrupters and switches in which the time for which the circuit is opened or closed is predetermined at will by means of a rotary disk as used in the art of automatic telephony. The object of the invention is to set the time of contact and the winding up of the mechanism by one single operation of the said disk. The device made in accordance with the present invention is especially 10 designed for photographic purposes, but of course the device may be employed in any case where a delayed action interrupter or switch is recommendable, especially when the setting of the delay is frequently varied.

15 The invention is illustrated by way of example in the annexed drawing in which a switch made in accordance with the invention is shown.

Figs. 1 and 2 are a front and a side view of the apparatus respectively. Fig. 3 is a sectional view taken along the line III—III of Fig. 2. Figs. 4 and 5 show the rear of the apparatus, Fig. 4 illustrating the switch in its ordinary position, Fig. 5 its position during the operation of switching, and Fig. 6 shows the drive by a falling weight 25 instead of a spring.

The apparatus substantially comprises three principal parts: a dial or selecting disk 1, an interrupter or switch 2, and a system of gears 3.

The dial or selecting disk 1 is entirely similar 30 to such used in automatic telephones. The numbers corresponding to the units of time to be selected are engraved beside the openings. A finger is inserted into one of the openings, and then the disk is rotated until the finger touches 35 the abutment 4. The latter is not rigidly fixed, but is movable under a certain pressure against the action of a spring 5 so that the disk, after the abutment has been touched by the finger may be rotated a little farther whereby half a unit of 40 time is added.

The dial 1 is rigidly secured to its shaft 6 journalized in two plates 7 and 8 which are held together by bolts 9, thus forming the frame of the apparatus. A spiral spring 10 adjacent to the plate 7 is fixed with one of its ends to this plate and with the other end to the shaft 6. Therefore by rotating the dial 1 and therewith its shaft 6 the spring 10 is wound up.

50 The shaft 6 projects from the frame plate 8 and has a plate 11 rigidly secured to it and carrying at one side a contact holder 12 and at the other side a lever 13 freely rotating around its axis 14. This lever 13 is connected at its upper end with a pawl 15 and carries at its lower end a movable contact 2 forming the interrupter or

switch which according to its position bridges either the contacts *a* and *b* or the contacts *b* and *c* carried by the contact holder 12.

A spring 16 retains the lever 13 as well as the movable contact 2 in their normal positions. 5 Another spring 17 maintains the desired pressure between the movable contact 2 and the contact holder 12. Finally, as soon as, owing to the rotation imparted to the dial, the end 20 of the pawl 15 has left the pin 21 a third spring 18 presses 10 the pawl 15 down so as to engage the cog wheel 19, located thereunder and offering a certain resistance to rotation.

The cog wheel 19 already forms part of the system of gears 3, because this wheel, even when 15 free to rotate independently of the shaft 6, remains rigidly connected by means of the socket 22 (passing through plate 8) with the other cog wheel 23 which is just the first of the series of regulating gears 3. The latter are not described, 20 as they are analogous to the common gears used in the mechanism of a time-piece.

The whole gearing 3 described above is to control, in addition to the function of regulating the velocity ratio of rotation, the speed during 25 the releasing phase for which purpose it is provided with an anchor carrying a counter-weight 24 to effect the desired speed.

The operation of the apparatus is divided into 30 two steps:

After having selected the desired length of time, the operator puts his finger into the opening of the dial 1 marked with the corresponding number, then he turns the dial from the normal or starting position shown in Fig. 4 until the finger touches the abutment 4 (or until the spring 5 is compressed) whereby the operated position shown in Fig. 5 is reached. During this rotation the spring 10 will have been wound up, and at the same time the pawl 15 will have passed as 40 many teeth of the cog wheel 19 as half-units of time were predetermined. On releasing the dial, the second step of the operation is automatically initiated, viz. the interruption or releasing phase. The spring 10 transfers its energy by the axis 6 to 45 the plate 11 and the lever 13, and thereby to the pawl 15 whereby the cog wheel 19 and the whole system of gears 3 regulating the rate of release are made to rotate. The pawl 15 by transmitting its power to the cog wheel 19 forces the lever 13 to turn around its axis 14 so that the movable contact 2 bridges the contacts *b* and *c* carried by the contact holder 12.

The whole apparatus as above described now 50 remains unchanged until the spring 10 is nearly 55

released; and before the release is completed, the projecting end 20 of the pawl 15 meets the pin 21 and forces the pawl itself to disengage the cog wheel 19. The pressure of the pawl on the 5 cog wheel now having ceased, the lever 13 returns under the action of the spring 16 into its position of rest, taking along the movable contact 2 and thus opening the circuit which up to this moment was closed by the contacts carried by the holder 10 12.

During the period referred to above the dial 1 will have slowly recovered its position of rest, and the apparatus is anew ready for use immediately 15 after the second step of the operation has been 15 completed.

It is obvious that other appropriate systems 20 may be substituted for the herein described systems of contacts and contact holders without departing from the gist of the invention. For instance, the above-described lever 13 could be replaced by one of the types of common mercury interrupters or commutators because this lever is perfectly fit for operating the said devices. On the other hand, the spring 16 may be replaced by an- 25 other driving means, for instance, by a falling weight as in a clock, as shown in Fig. 6, in which a sprocket wheel 28 is mounted on the axis 6 and a chain 26 is wound around the said sprocket wheel and carries a weight 27.

30 We claim:—

1. Apparatus for interrupting an electric current for a predetermined time comprising a frame, a rotary dial, a central shaft rigidly connected therewith and journaled in the said frame, a 35 spring connected at one of its ends to the said shaft and at its other end to the said frame, a

plate rigidly connected with the said shaft, a number of contacts secured to the said plate, a bridge mounted on the said plate capable of being displaced so as to touch part of the said contacts, a pawl resiliently secured to the said bridge and adapted to engage a cog-wheel loosely mounted on the said shaft so as to offer a certain resistance against rotation, the said cog-wheel being driven by the said pawl in the same sense, as the dial is driven by the first-named spring, and an abutment disengaging the said pawl after the dial 10 has returned to its normal position. 5

2. Apparatus for interrupting an electric current for a predetermined time comprising a frame, a rotary dial, a central shaft rigidly connected therewith and journaled in the said frame, a 15 spring connected at one of its ends to the said shaft and at its other end to the said frame, a plate rigidly connected with the said shaft, a 20 number of contacts secured to the said plate, a lever rotatably mounted on the said plate, a movable contact carried by the said lever, a spring tending to press the movable contact against a 25 number of the first-named contacts, a spring tending to turn the said lever in the same sense as the first-named spring turns the dial, a pawl resiliently secured to the end of the said lever and adapted to engage a cog-wheel loosely mounted on the said shaft so as to offer a certain resistance 30 against rotation, the said cog-wheel being driven by the said pawl in the same sense as the dial is driven by the first-named spring, and an abutment disengaging the said pawl after the dial has returned to its normal position. 35
